UNITED STATES PATENT OFFICE.

FREDERICK W. LINAKER, OF DUBOIS, PENNSYLVANIA, ASSIGNOR TO THE VULCAN SOOT CLEANER CO., OF PITTSBURG, PA., OF DUBOIS, PENNSYLVANIA, A CORPORATION OF NEW JERSEY.

FUEL-ECONOMIZER SOOT-CLEANER.

1,160,729.

Specification of Letters Patent. Patented Nov. 16, 1915.

Application filed November 3, 1914. Serial No. 870,124.

To all whom it may concern:

Be it known that I, FREDERICK W. LINAKER, a subject of the King of England, residing at Dubois, in the county of Clearfield, 5 and State of Pennsylvania, have invented certain new and useful Improvements in Fuel-Economizer Soot-Cleaners, of which the following is a specification.

This invention relates to improvements in 10 fuel-economizer soot-cleaners and has for its primary object to provide in an economizer, a cleaning fluid distributing pipe or pipes for directing a cleaning fluid, preferably steam, upon the exterior surfaces of the tubes 15 of the economizer whereby to effectually free the latter of soot.

A further object of the invention is to provide in an economizer, a fluid distributing pipe or pipes so constructed and arranged 20 as to discharge the cleaning fluid between the rows of tubes of the economizer in streams along lines or paths oblique to the axis or axes of the distributing pipe or pipes.

25 A still further object is to provide in an economizer, a soot cleaning means in the form of a fluid-distributing pipe or pipes adapted to discharge cleaning fluid in oblique jets or streams, and capable of oscillatory movement whereby to cause said distributing pipe or pipes to vary the angularity or obliquity of the streams of cleaning fluid, thereby adapting the latter to cover a wide radial area and to thus effect the removal 30 of accumulated soot from all of the rows of the economizer tubes.

Fuel economizers, as is well known, are utilized for the purpose of heating water preliminary to its introduction into the 40 boiler, and for this purpose use is made of the waste gases and other products of combustion, the economizer being generally located in the path of travel of such production leading from the boiler or boilers to the 45 chimney or stack, the economizers comprising a plurality of spaced vertically-extending tubes, the upper and lower ends of which are connected by headers to provide a circulation of water therethrough. As the tubes 50 are located in the path of travel of the products of combustion, the outer surfaces of the tubes quickly collect soot particles carried by such products, destroying the maximum application of heat to the tubes. Tube

cleaners which travel vertically over the 55 outer surfaces of the tubes have heretofore generally been employed for removing such soot particles and scale as may collect on the tubes, these cleaners acting in a manner similar to a scraper. Difficulty has been encountered in the use of cleaners of this type for economizers, in that the scraping cleaners oftentimes may not be operated to effectually clean the tube throughout its 60 length, and also that they drive or force the 65 soot ahead of them, causing it to collect in masses which are not easily carried off by the natural draft.

To overcome the above and other objections to the cleaning of economizer tubes by a 70 scraping action, I arrange among the tubes as heretofore stated, a distributing pipe or pipes for a cleaning fluid, capable of being operated at any time without closing down the operation of the furnace or the economizer, and which in operation in addition to 75 effectually cleaning the economizer tubes of soot, aid the natural draft in carrying off the removed particles, and enabling me at all times to procure a maximum amount of 80 service from the economizer.

The nature of the invention will be readily understood as the same is hereinafter disclosed, and the said invention consists in the improved construction, combination and arrangement of parts, hereinafter fully described, illustrated in the accompanying drawings, and particularly pointed out in the appended claims.

In the drawings, in which similar reference characters indicate similar parts in each of the views: Figure 1 is a side elevation partly broken away of an economizer of the well-known Sturtevant type, with a soot cleaner in accordance with my invention applied thereto. Fig. 2 is a plan view of the same partly broken away.

A fuel economizer of the Sturtevant type comprises a jacket or setting 1 which encloses the vertically-disposed economizer tubes 2 connected in the usual manner at the upper and lower ends by headers 3. The tubes 2 in this type of an economizer are in staggered form or relation, and in order to effectually remove the accumulated soot 100 from the tubes, it is necessary to project the cleaning agent between the tubes in streams or paths oblique to the axis or axes of the 105

- distributing pipe or pipes that is arranged among the tubes for cleaning purposes.
- In the here chosen illustration of my invention, I have shown two distributing pipes 4 arranged one above the other in vertical longitudinal alinement, these pipes being journaled in bearings 5 on the opposite side walls of the setting or jacket 1. Obviously, but a single pipe, or as many of the pipes as desired may be arranged, according to the size of the economizer in which the cleaner is arranged. Whether there be one or more pipes, each pipe is closed at its inner end, its outer end being in communication with a branch pipe 6 connected with a supply pipe 7, which latter is provided with the usual shut-off, drain valve, etc. Each branch pipe 6 is also provided with a shut-off valve 6'. Each pipe 4 is provided with spaced nozzles 8 so disposed with relation to the axis of the pipe, that the cleaning agent is directed in jets or streams along oblique paths or lines between the rows of tubes 2 to remove accumulations of soot from the outer surfaces of the tubes, these oblique paths or lines upon which the jets or streams of the cleaning agent are projected, being clearly illustrated in Fig. 2 of the drawings, the lower pipe projecting the jets or streams as shown by full lines and arrows, the upper pipe projecting the jets or streams as shown by broken lines and arrows, so that the streams from the one pipe intersect and cross the paths of streams from the other pipe.
- In order that the pipe or pipes 4 may be oscillated or partially rotated, the outer ends of these pipes connect by means of a swivel joint 9 with the branch pipe 6, suitable means being provided for operating the pipes 4. This means obviously may be a hand wheel 13 on each pipe 4, as shown on the lower pipe in Fig. 1, or it may be a means as shown on the upper pipe in Fig. 1 consisting of a sprocket wheel 10 upon the pipe 4, over which passes a sprocket chain 11, having the ends connected to rods 12, these rods projecting down to a point where they are within easy reach of the operator and provided on other lower ends with hand grasps 14. By pulling alternately on the rods 12 the pipe is revolved as desired, and since the nozzles 8 are disposed around the pipe or pipes 4 and are so disposed that their discharge ends are oblique to the axis of the pipe, the jets or streams of cleaning fluid are projected on oblique lines between the rows of tubes 2, the oscillating movement of the distributing pipe or pipes varying the radial paths or the streams of fluid issuing from the discharge nozzles, insuring a thorough cleaning of the water circulating tubes of the economizer throughout their length, such wide diffusion of the cleaning fluid permitting it to permeate all of the spaces between the water tubes and any surfaces within the economizer casing or setting where soot may find lodgment.
- It will be understood that the invention is susceptible to modifications in its structural details, such as in the manner of operating the distributing pipes, and in the number or distribution of these pipes among the tubes so as to effectually clean the latter, and like modifications as may fall within the terms and scope of the invention as claimed.
- What I claim as new is:—
- The combination with a fuel economizer system having rows of vertical water-circulating tubes and located in the path of travel of the products of combustion, the rows of tubes being in staggered relation, of fluid distributing pipes rotatably mounted in the casing of the economizer and disposed between the said tubes, nozzles carried by each pipe and disposed around the pipes to discharge cleaning fluid in jets or streams on lines or paths oblique to the axes of the pipes, said nozzles also disposed to project the fluid in the spaces between rows of tubes, the nozzles carried by one blow pipe being arranged to project the cleaning fluid on paths or lines which intersect and cross the paths or lines of streams of cleaning fluid issuing from another pipe, and means for rotating the pipes to vary the angularity of said jets or streams with respect to the vertical axes of water-circulating tubes.
- In testimony whereof I affix my signature in presence of two witnesses.

FREDERICK W. LINAKER.
